ABSTRACT OF THE DISCLOSURE

A method of lining a nut with a low friction fabric includes the steps of wrapping the fabric on a threaded sectional preform, conforming the fabric to the threads of the preform by wrapping with a string or cord, removing the string while placing the preform in the nut, pressing from the inside of the preform to press a resin bondable surface of the fabric onto the nut threads, removing the preform sections, further pressing the fabric onto the nut threads and curing the resin to finally bond and secure the fabric to the threads of the nut.

This invention relates to a method of making a low friction, precision fabric lined internally threaded article, i.e. a fabric lined nut.

Load bearing nuts for use for example in heavy duty linear actuators must have low frictional resistance with their mating screw. Lining such nuts has been contemplated to substantially lessen the frictional resistance. One known solution is to line the nut with a fabric having a low friction facing material. This, however, is extremely difficult to accomplish in practice because it is very difficult to conform flexible low friction material to internal threads and still obtain the precision and load bearing capability required. It was not previously thought to be possible to line the threads of a nut with a fabric and obtain anything like $\frac{1}{1000}$ inch tolerance. This invention solves, however, that problem in a unique way by lining the nut with a low friction fabric and specifically, includes the steps of pulling the fabric tight over the crest and sides of a threaded preform mandrel, inserting the preform and fabric in a nut, securing the fabric to the nut, compacting and curing the lining so that the final product results in a precision lined nut where at least three of the four surfaces of the nut thread (assuming an acme thread) results in a very close tolerance, equivalent to that of precision machined nuts.

The purpose of this invention, therefore, is to provide a method of lining a nut with low friction fabric material to a precision tolerance of the order of 1 mil, thereby allowing reduced friction with a mating screw.

To illustrate in greater detail the method of this invention, there is set forth in the following drawings both the method steps as well as the structure of the apparatus in detail, employed in the method of this invention.

In the drawings:

FIGURE 1 is a block diagram of the specific method steps involved in this invention with descriptive legends and reference to subsequent figures for the details of the specific steps;

FIG. 2 is a perspective view of a tri-section preform mandrel with bolt and washer to hold sections together;

FIG. 3 is a cross-sectional view of the tri-section preform mandrel with very thin barrier sheet and low friction fabric wrapper thereupon;

FIG. 4 is a perspective view illustrating conforming of the fabric to the mandrel by wrapping same with a strong string or stout cord;

2

FIG. 5A is an enlarged cross-sectional detail view of the low friction fabric wrapped by the cord and made to conform to the thread crests and a portion of the thread sides of the preform mandrel;

FIG. 5B shows in perspective a partial top view of the wrapped preform showing overlap of the low friction fabric and a tab of the barrier sheet;

FIG. 6 is a perspective view showing the step of removing the string or cord as the preform mandrel is turned and elevated into a nut without touching the nut;

FIG. 7A is a perspective view showing the segmented preform mandrel inside the nut with a pressing member pressing down on one segment and with the nut supported in a cradle;

FIGS. 7B and 7C are perspective views similar to FIG. 7A in showing the pressing member pressing the other mandrel segments;

FIG. 8 is an end elevation view showing the three segment preform mandrel after the fabric has been pressed against the internal threads of the nut;

FIG. 9 is an end elevation view showing preform mandrel segment B being removed from the assembly;

FIG. 10 is an end elevation view showing preform segment A used with pressing member for final pressing of the fabric liner into the threads of the nut to compact same;

FIG. 11 is a perspective view of lined nut with a curing mandrel therein; and

FIG. 12 is an enlarged sectional view through a section of a lined thread.

The invention will be described in detail below with reference to the accompanying drawings and with the understanding that the description is of a preferred embodiment.

The nut to be lined in the preferred embodiment may be used as the nut of a linear actuator which includes a complementary screw. The nut is designed to have the largest possible area of bearing surface available for each increment of nut axial length for given major and minor diameters. For example, the nut preferably has an acme thread with four starts, and in one successful commercial embodiment the nut threads are of one inch pitch, four and one-half inches minor diameter, five and one-half inches long, and the nut is made of SAE 4340 alloy steel heat treated to 500 BHN. The nut is lined with fabric to fit the screw threads with zero clearance between their two faces and their major diameters and some clearance between their minor diameters.

The fabric with which the nut is to be lined internally is of compound weave with bondable threads predominantly on the back side to contact the nut and "Teflon" threads predominantly on the front side to contact the screw. The "Teflon" threads are spun or wound of "Teflon" filaments and may include some bondable material filaments.

The fabric is first supported on a preform mandrel 14 as in FIGS. 2 and 3. The mandrel comprises three segments which are held together by a bolt nut and washer assembly 16. The mandrel is formed from a threaded cylinder initially having threads 18 thereon corresponding to the threads of the nut to be lined with appropriate clearances. This threaded cylinder is cut axially to provide three segments A, B and C (FIG. 3), with a portion of the circumference removed at each axial cut so that the assembled mandrel (which looks like a three-cornered hat) is of a lesser diameter than the internal diameter of the nut and may move freely into the nut without touching the nut threads. The preform mandrel threads are preferably cadmium plated so that resin bonding the fabric will not stick to them. The fabric to be wrapped on the preform mandrel 14 is a pre-dried, but uncured, resin im-

pregnated fabric 22 with a low friction material such as "Teflon" on one side and "Dacron," cotton or the like, on the other side. An oversized rectangle of this fabric is cut to size for wrapping over the preform mandrel and barrier sheet 20 with excess length at both ends. The bias of the filaments of the fabric may optionally correspond with the pitch of the threads. After cutting and while still laid out flat, the bondable side of the rectangle of fabric is roller coated with resin and allowed to air dry to a tacky dough-like consistency. This bondable side is to be outside on the preform so as to contact the threads of the nut. The amount of resin is only that later needed to mechanically support the fabric threads and hold the fabric in the nut. In other words, the resin is not a filler as the back of the fabric is to be in direct contact with the nut.

The assembled preform mandrel 14 is first wrapped with a barrier sheet 20, such as "Teflon" 1 mil thick, to further prevent adherence of the low friction resin impregnated fabric to the preform. Note that between mandrel segments A and C the barrier sheet has an inwardly extending tab 20_t which will aid in its removal at a later step in the process. The fabric is then wrapped over sheet 20 around the preform mandrel and overlaps the start of the fabric to provide the overlap 22_o, see FIG. 5B. Note that the portion of barrier sheet 20 opposite tab 20_t lies beneath the overlap 22_o and that overlap 22_o is located on mandrel segment A and opposite segment B.

The next step shown in FIG. 4 and in detail in FIGS. 5A and B is to at least partially conform the fabric to the preform and especially conform the fabric to the crest and a portion of the sides of the threads of the preform mandrel by wrapping the fabric with a removable strong string or cord 24 positioned in the thread roots. In pushing the fabric into the thread roots the cord should shorten the length of the rectangular piece of fabric within predetermined limits. Too much shortening will result in excess "ballooning" over minor nut diameter. If, on the other hand, it is not enough, then the fabric will not "bottom" in the major nut diameter. For this purpose the cord or string may be as wide as the thread root requires. Note that there is some excess fabric over the crests of the mandrel which is not less than the amount needed to allow the fabric to extend across the roots between the threads.

With the preform mandrel disposed vertically and a nut 26 to be lined held rigidly above the mandrel and in alignment therewith and with the upper ends of the cords 24 tied to cord pullers (not shown) the preform mandrel is next rotated and elevated into the nut while the taut cords 24 unwind from the preform mandrel directly under the nut as the preform mandrel is completely inserted within the nut. The purpose of unwinding the cords just before the mandrel with the fabric thereon moves into the nut is to leave no time for the uncured fabric to droop from the threads on the preform mandrel and so that the fabric is moved into the nut without touching the threads of the nut.

Once the fabric is positioned inside the nut with the segments, the entire assembly is laid in cradle 30 with segment B downward. The segments are then to be light pressed by a pressure member 28 with a pressure of the order of 50 p.s.i. on the mandrel segment to cause the material to stick to the inside of the nut while supported in cradle 30. The segments are light pressed in a particular sequence as shown and with reference to overlap 22_o. As shown in the drawings, segment B is pressed first as shown in FIG. 7A and segment C is similarly light pressed, to cause a gap to be developed between segments C and A as shown in FIG. 7B. Finally, segment A is light pressed and this causes the gap between segments A and C to become larger as shown in FIG. 7C.

Following this initial light pressing operation, all three mandrel segments A, B and C are in the positions shown in FIG. 8 so that two mandrel segments may then be re-

moved as shown in FIG. 9. Mandrel segment A should be removed and either segment B or C should also be removed. The remaining mandrel segment is given an intermediate press with a press load of 1000 p.s.i. while rotatably stepping the nut in the direction of the arrow, see FIG. 10, to effect further compacting of the fabric in the nut threads. This stepwise rotation of the nut 26 in cradle 30 with pressure member 28 provides non-isostatic pressure on overlapping steps of about 1" each with the remaining segment proceeding toward and over the tab 20_t and fabric overlap 22_o and back approximately to its original position.

The fabric is now compacted into the nut threads but is not yet cured. The remaining mandrel segment should be removed for and during the next step and the "Teflon" barrier sheet separating the resin containing low friction fabric and the mandrel threads is also removed by merely pulling on non-sticking tab 20_t and stripping the sheet.

Next the resin of the fabric lined nut is dried by placing the lined nut in an oven. The drying is preferably accomplished at a temperature of 280° F. for the time necessary to dry out the particular resin coated fabric. In the case of a typical material this would take in the order of 15 minutes. This drying step leaves resin with microscopic pores as a result of the solvents being driven off, such that it is an open-cell cellular material to a limited degree.

The lined nut is then removed from the oven and allowed to cool. Following cooling the fabric overlap 22_o is next cut with a knife in a straight axial line over the threads and the edges of the fabric are repositioned so that they will now abut.

The nut is now replaced in cradle 30 and the fabric is given a heavy press using one preform mandrel segment in another step-by-step sequence as illustrated in FIG. 10. The pressure here required is in the order of 2000 p.s.i. to establish a precise thickness to the layer so that the nut can be screwed onto its mating part. This heavy press is to be sure that all filaments are buried in resin with only the top sides of the "Teflon" filaments exposed and to compact all filaments in the open pored resin.

The next step is the final curing. For that purpose and as shown in FIG. 11, the lined nut with excess fabric at the ends of the nut is threaded on a cadmium plated curing mandrel 34 which is externally threaded to duplicate the screw threads of the preform mandrel. The curing mandrel is cylindrical and is proportioned so that it will expand and contract in proper relation to expansion and contraction of the nut. The whole assembly while standing on the end of the curing mandrel is heated in an oven at a temperature of several hundred degrees Fahrenheit. With a typical material, a temperature of 325° F. for a period of four hours may be required.

The assembly is now removed from the oven and cooled in air with the curing mandrel standing on end. After cooling the mandrel is removed by turning the nut off carefully. The selvage edges 22_s may now be cut flush with the end of the nut. The compacted fabric and the cured resin should have a thickness leaving in the order of only $\pm .0005"$ clearance between the nut and screw for near zero axial and radial play. Following the trimming of the material or fabric extending out the ends of the nut, the product is finished.

FIG. 12 is a sectional view through the finished lined nut, with the thread configuration of the preform mandrel shown in phantom. It is noted that the fabric completely conforms to the thread sides and roots of the nut as it has previously conformed to the crest and sides of the threads of the preform mandrel. The preform mandrel had excess clearance in its thread root providing excess clearance on the minor diameter of the nut, i.e., on the threaded crest of the nut.

As can be seen, this invention provides a unique method of lining an internally threaded article such as a nut

involving the essential step of placing a lining fabric on a preform and conforming it over the crest and sides of the preform so that when the preform is inserted into the nut, the fabric is compacted under the nut threads and cured so that the nut will have precision threads therein.

While the production of the instant lined nut has been described with details as to specific steps, treating times and temperatures, these limits are only given as illustrations and are not to be deemed limiting. It will be understood that numerous changes may be made in the details of construction, arrangement and operation without departing from the scope and spirit of the invention, especially as defined in the following claims.

What is claimed is:

1. A process for lining internal threads of a nut with a low friction flexible fabric, comprising:
  - (a) wrapping a preform mandrel having threads thereon corresponding to mating threads of the nut with the low friction fabric which has a resin bondable surface and an antifriction surface, the antifriction surface being positioned adjacent the preform threads,
  - (b) conforming the fabric to the crest and at least a portion of the sides of the threads on the preform mandrel by wrapping an elongated flexible material such as a cord around the fabric, the cord positioned in the thread roots of the preform threads,
  - (c) removing the elongated flexible wrapping material while inserting the preform with the fabric conformed to the threads thereon into the nut without contacting the threads of the nut with the fabric,
  - (d) bonding the resin bondable surface of the fabric to the nut by pressing the resin bondable surface against the nut, removing the preform, and curing the resin of the resin bondable surface to finally bond and secure the fabric to the internal threads of the nut.
2. A process as in claim 1 wherein the pressing in-

5

cludes initially light pressing with a pressure in the order of 50 p.s.i., followed by intermediate heavier pressing with a pressure in the order of 1000 p.s.i., then drying the resin, and finally utilizing heavy pressing in the order of 2000 p.s.i. prior to curing the resin.

3. A process as in claim 2 wherein the preform mandrel is sectional and the pressing is accomplished using one section of the preform mandrel.

4. A process as in claim 3 further comprising utilizing a barrier sheet between the threads of the preform mandrel and the low friction flexible sheet material to prevent the resin bonding from causing the material to stick to the preform.

5. A process as in claim 2 wherein the curing is accomplished utilizing a curing mandrel positioned adjacent the internal threads of the nut.

6. A process as in claim 1 wherein the preform mandrel threads are cadmium plated.

7. A process as in claim 1 wherein the low friction fabric is in the form of a sheet and the ends of the fabric sheet are wrapped on the preform in overlapped relationship, and after final bonding and securing the fabric to the nut the overlapped material is cut off and removed.
